UNITED STATES PATENT OFFICE.

MELVIN B. BENSON, OF SUPERIOR, WISCONSIN.

TELEMOTOR.

1,374,180.

Specification of Letters Patent. Patented Apr. 12, 1921.

Application filed December 29, 1916. Serial No. 139,528.

To all whom it may concern:

Be it known that I, MELVIN B. BENSON, a citizen of the United States, residing at Superior, in the county of Douglas and 5 State of Wisconsin, have invented certain new and useful Improvements in Telemotors, of which I do hereby declare the following to be a specification.

My invention relates to telemotors, and 10 has for its primary object the provision of improvements in steering gear for vessels. It has for a further object the provision of improved means for actuating the supply, or exhaust valve of an engine distant from the 15 station of the operator. With these and other objects in view, it consists of the constructions, combinations and arrangements of parts hereinafter described and claimed.

In the drawings, Figure 1 is a plan view, 20 partly in section and partly in diagram, of my said invention. Fig. 2, is a central vertical longitudinal section of the hereinafter described controller box and pedestal, partly broken away, and of parts positioned thereon, or therein. Fig. 3, is a front elevation partly broken away, of the hereinafter described auxiliary controller case. Fig. 4, is a vertical longitudinal section approximately on the line A—B—C—D of Fig. 3. 30 Fig. 5, is a vertical transverse section approximately on the line E—F—G—H of said Fig. 3. Fig. 6, is a fragmentary plan view of the hereinafter described reciprocating collector bar, showing the hereinafter described insulation pad interposed therein. Fig. 7, is a fragmentary plan view partly in diagram showing my invention as applied to the direct operation of a steering gear from which a steam, or gas engine is omitted.

40 Heretofore it has been customary to operate the steering gear on large vessels by means of a hand steering wheel having a hub connected with the tiller by cables or chains extending aft from a pilot house near the front of the vessel; or else by oil tele- 45 motors in which oil pipes extend aft from a cylinder in the pilot house to a cylinder near the rudder head; a piston in the pilot house cylinder being operated by the steering wheel and a piston in the aft cylinder being driven by the piped oil and connected to the valve of a steam steering engine. Where the cable or chain connections are used on an empty vessel, they tend to become 50 slack; or when used on a laden vessel they tend to stretch, or to become so taut that

they bind if the ship is of considerable length. In an oil telemotor, air bubbles tend to accumulate in the pipes and to become compressed therein so that the cylinder 60 pistons do not work in accurate accordance with the steering wheel and the rudder does not take the position indicated by such steering wheel. Further, the oil tends to leak around one end of the piston and so permit 65 the rudder to work toward center when the steering wheel and oil pistons are at one end of their travel.

In the accompanying drawings, 1 is a controller box of any suitable form or construction, mounted on a support of any suitable form or construction, as on a pedestal 1^a. Said controller box, when used in connection with a steering gear for vessels, is preferably positioned in a pilot house in the fore part 70 of such vessel. Within said controller box are preferably positioned electric contacts 2 and 3, of the collector-bar type; said contacts being insulated from each other and from the adjoining box by any suitable insulating material, of any suitable structure or form, as by the insulating plate 4, supported by any suitable means, as by the posts 5. Within said box are also positioned a plurality of electric contact points, 6, insulated from each other in any suitable manner, or by any suitable means, as by an insulation plate 7 supported by any suitable means, as by a bracket 8 and posts 9. Electrically connecting said contact bar 2 and 80 any one or another of said contact points 6, is a conductor 10, pivotally mounted intermediate of its ends on any suitable support as upon a post 11. A thimble 11^a is preferably interposed between said post 11 and 85 said conductor, to which thimble said conductor is secured and with which it is adapted to turn. Said conductor is also preferably insulated from said post and thimble in any suitable manner or by any suitable 90 means, as by a thimble 10^a of insulating material. Said thimble 11^a extends above the cover of said box, and there is mounted thereon an operating lever 12 by which said thimble and said conductor may be oscillated so that one end of said conductor 10 will come into contact with any one or another of said contact points 6.

Positioned within said box is a plate or fork 13, which is pivotally mounted upon 110 any suitable support, as upon said post 11, from which it is preferably insulated. Said

plate or fork carries a contact pin, 14 preferably insulated therefrom and electrically connected in any suitable manner, as by a wire 14^a, with a contact point 14^b carried by and insulated from said conductor 10 and adapted to contact with said bar 3. Said contact 14 extends into the path of oscillation in one direction of said conductor 10, and when said conductor is moved 5 slightly in such direction it contacts therewith and closes a circuit including said bar 2, conductor 10, pin 14, wire 14^a, point 14^b, and bar 3. The further movement of said conductor 10 in such direction maintains 10 said circuit and at the same time causes the plate or fork 13 to swing on its pivot. Said plate or fork also carries a stop 15, extending into the path of said conductor 10 at the opposite side thereof, so that when the conductor 10 is moved away from said contact 14 for a very short distance it will bear 15 against said stop and cause said plate or fork to swing on its pivot, whereby the contact point 14 is caused to follow said conductor 10 at a very short distance therefrom. Said plate or fork is also provided 20 with a constant brake of any suitable form, structure, or position, as with a brake shoe 16 carried thereby and bearing upon a brake rail 16^a, which may be supported in 25 any suitable manner, as by posts 16^b. The bar 2 is connected at all times in any suitable manner as by a wire 17 with the positive pole of a suitable source of electricity, as the generator 18; said bar 2 being used merely in preference to connecting 30 said wire 17 to the conductor 10. Said bar 3 is connected at all times in any suitable manner, as by a wire 19, with the negative pole of said generator; said bar 3 being used merely in preference to connecting 35 said wire 19 to a contact point carried by the plate 13. Formed, or interposed in said wire is a relay coil 19^a. Said contact points 40 6 are at all times respectively connected as by wires 6^a with corresponding contact points 6^b insulated in any suitable manner as by a stationary insulation plate 20 (through which they extend), from direct 45 communication with each other. One or another of said contacts 6^b—or a group comprising all but a varying one of them—is adapted to contact at all times with a movable contact member, preferably comprising a reciprocable contact bar 21, extending beneath all, or all but one of said points 6^b. Interposed in the contact surface of said bar 21, at a point beneath the central one of said contacts 6^b when said bar 50 is in central or neutral position, is an insulation pad 21^a. Said insulation pad is adapted to be moved with, or by said reciprocating contact, in either direction, into opposing position to any one or another of 55 said contacts 6^b, whereby the contact 6^b

thus opposed is temporarily insulated from said reciprocating contact 21. Said reciprocating bar or contact is mounted upon any suitable form or structure of carrier, as upon a slide plate 22, from which it is 60 insulated in any suitable manner as by an insulation plate 23. Said slide plate is mounted in any suitable guides, as the walls of an auxiliary controller box 24. Said slide plate is provided with a fixed nut 22^a 65 adapted to engage a drive screw or worm 25, by which said plate is reciprocated. Said screw is driven by an electric motor, A, through suitable intermediate transmission mechanism, as the sprocket wheel 26. 70 80 belt 27, sprocket 28, gear 29 and pinion 30. Contacting with said reciprocating contact at all times, is a stationary contact point 31 which is, in any suitable manner, as by a wire 31^a, connected with the negative pole of said generator, said contact 31 being used merely in preference to a direct attachment of wire 31^a to said reciprocating contact 21. It will be observed that when 85 said contact 31 is employed, the reciprocating contact 21 will be made long enough to keep in contact with it when said insulation pad has moved to its farthest point of travel away from said contact 31; said reciprocating contact being shortened in the 90 drawings because of insufficient space. Interposed or formed in said wire 31^a is a relay coil 31^b. A relay armature 32 is adapted to be governed by said coil 31^b, and is opposed by a contact point 33 of a normally 100 open contact, which point 33 is connected with the positive pole of said generator by any suitable conductor, as by a wire 34. Said armature 32 is also opposed by a point 35 of said normally open contact, which 105 point 35 is connected by any suitable conductor, as by a wire 36, with points 37 and 38 of a normally open and a normally closed contact, respectively, said points 37 and 38 being carried by a relay armature 39 governed by said coil 19^a. The point 38 of said 110 normally closed contact is electrically connected through its stationary opposing contact point 38^a and a wire 38^b with the positive pole of said motor, the negative pole 115 of which motor is connected as by a wire 40^a with the stationary contact point, 40, of a normally closed contact, the opposing point 40^b of which is carried by said armature 39 and is connected in any suitable 120 manner, as by the wires 40^c and 19, with the negative pole of said generator. Said normally open contact 37 is opposed by a stationary contact point 41, which is connected by any suitable conductor, as by 125 wires 41^a and 40^a to the negative pole of said motor, the positive pole of said motor being connected by any suitable conductor as the wires 38^b and 42^a with a stationary contact point 42 of a normally open contact, 130

the opposing point 43 of which is carried by said armature 39 and is connected by the wires 40^a and 19 with the negative pole of said generator. Where practicable, full distance parallel wires to the same poles are avoided by establishing branches from a main line to points to be connected therewith. The relay armature 32, or a single contact carried thereby is adapted in operation to connect the contact points 33 and 35.

Said motor is connected mechanically in any suitable manner, as by said pinion 30, gear 29, a pinion 44, a gear 45, a drive screw 46, a nut 47^a, a slide plate 47, a connecting rod 48, a walking beam 49 and a connecting rod 50, with any desired mechanism to be operated, as to the valve stem 51 of the valve 52 an engine (not shown) or by any desired means, as by said pinion 30, gear 29, pinion 44 and gear 45 and screw or worm 46, to any suitable form of steering gear, as to a gear comprising a drum 53 and flexible hauling means 54 wound thereon and engaging a segment 55 secured to a rudder post 56.

In operation, assuming the conductor 10 to be midway between the contact pin 14 and the stop 15 and to be in contact with the central one of the contact points 6, and that the insulation pad 21^a is in opposition to the central contact point 6^b, and that the armature 32 is idle and the contact points 33 and 35 are not bridged, and that the armature 39 is down, there will be no flow of current and the device will be idle. If then the conductor 10 be swung toward the stop 15 and into contact with the next point 6 on that side of the center, a circuit will be closed thereby from the generator to bar 2, thence to conductor 10, thence to point 6, thence to point 6^b, thence to reciprocating contact 21, thence to contact point 31, thence through the coil 31^b to the opposite pole of said generator. The energizing of coil 31^b causes the armature 32 to bridge contact points 33 and 35, thus closing a circuit from said generator through contact points 33 and 35 and through points 38 and 38^a to said motor, thence through contact points 40 and 40^a to the opposite pole of said generator. The energizing of the motor causes it, through the transmission mechanism described, to turn said screw 25, whereby the reciprocating contact is drawn over until the insulating pad 21^a is in opposition to the point 6^b in circuit, whereupon said point 6^b will become insulated and the circuit will be opened, causing the armature 32 to fall thus opening the circuit through said motor. At the same time that said motor has been operating said screw 25, it has also been operating said engine valve, or such other mechanism as may be connected to said motor instead of such valve. The operation may be repeated in the same direction by moving

the conductor 10 to the second point 6 at 65 the same side of the center, and so from point to point; or the single operation may be prolonged by advancing the conductor 10 several points in the same direction by a continuous movement.

To reverse the operation, the conductor 10 is moved in the opposite direction and into contact with the contact pin on point 14, and, continuing into contact also with any point 6 on the corresponding side of the last 70 previous stopping place of said conductor 10. When said conductor 10 contacts with the point 14, it closes a circuit from said generator through said bar 2, thence to conductor 10, thence to the point 14, thence 75 through wire 14^a to the point 14^b, thence to the bar 3, thence through the coil 19^a, thence to the opposite pole of said generator. The energized coil 19^a operates the armature 39, which carries the points 37 and 43 into contact with the points 41 and 42, respectively, which is preparatory to routing the current reversely through said motor. Such circuit being established and maintained, the subsequent contact of conductor 10 with a point 90 6 in the path of its continued advance will close a circuit, as before, from the generator through bar 3, conductor 10, point 6, point 6^b, reciprocating contact 21, point 31, and coil 31^b to the opposite pole of said generator. The energized coil 31^b thereupon operates the armature 32, causing it to bridge contact points 33 and 35, thereby closing a circuit from said generator through contacts 100 33 and 35, thence (reference to connecting wires being omitted for brevity), through contacts 37 and 41, thence through said motor (reversely), thence through contacts 42 and 43, thence to the opposite pole of said generator. The reversal of the current 105 through said motor reverses the motor, which reverses the screw 25, whereby the reciprocating contact is thrust over until the insulating pad 21^a is in opposition to the point 6^b which is connected with the point 110 6 with which said conductor 10 is temporarily in contact, whereupon the motor circuit is opened. By moving the support 10 out of contact with any and every point 6 in either direction the motor circuit is opened 115 arbitrarily without respect to the position of said pad 21^a. By moving the support 10 out of contact with the point 14, the reversing circuit is opened.

While I have described the preferred form 120 of my said invention, it is obvious that it may be modified or altered in various details of construction, as by substituting mechanical equivalents for certain mechanical parts shown, or by substituting electrical equivalents for certain electrical parts shown, or by transposing certain contacts or conductors, or by changing the form, propor-

tions or dimensions of certain parts, or in other ways all within the spirit and scope of and of certain of my claims.

What I claim is

- 5 1. The combination of a source of electricity and a motor in circuit therewith, said circuit including a normally open contact, a second normally open contact and a third normally open contact; a second circuit including said source, a normally open contact and a relay coil; a third circuit including said source, a normally open contact, a normally closed contact and a relay coil; manually operable means for closing the 10 normally open contact of said second and third circuits respectively, means adapted to be automatically operated by said motor for opening the normally closed contact of said third circuit after the closing of the normally open contact of said third circuit, means governed by the coil of said third circuit for closing one of the normally open contacts of said first circuit, and means governed by the coil of said second circuit for 15 closing the other normally open contacts of said first circuit.
2. The combination of a source of electricity and a motor in circuit therewith, said circuit including a normally open contact; a second circuit including said source, a plurality of normally open contacts in parallel, a plurality of normally closed contacts in parallel, each of said normally closed contacts being in a series with a corresponding 20 one of said normally open contacts of said second circuit, means for closing any one of said normally open contacts of said second circuit, means for automatically opening the corresponding one of said normally closed contacts after the closing of any one of said normally open contacts of said second circuit, and means governed by said second circuit for closing the normally open contact of said first circuit, the contact opening 25 means employed in said second circuit being governed by said first circuit.
3. The combination of a source of electricity and an electric motor in circuit therewith, said circuit including a normally open contact, a second normally open contact and a third normally open contact; a second electric circuit including said source, a normally open contact and a relay coil; a third circuit including said source, a normally open contact a normally closed contact and a relay coil; means for closing the normally open contact of said second circuit, said means comprising a hand lever, a movable conductor arm operated thereby and electrically 30 connected to one of the poles of said source, 60 a yielding support, a contact carried by said support and extending into the path of said conductor arm, and electrically connected with the opposite pole of said source, said support being provided with a constant 65 brake for retarding its movement, said support having a stop extending therefrom and adapted to limit the distance of travel of said conductor arm away from said contact carried by said support and to cause said 70 support and the contact carried thereby to follow said conductor arm in retractive direction, said conductor arm being also adapted to close the normally open contact of said third circuit; means for automatically 75 opening the normally closed contact of said third circuit at a predetermined time after the closing of the normally open contact thereof, means governed by the relay coil of the third circuit for closing one of 80 the normally open contacts of said first circuit, and means governed by the relay coil of said second circuit for closing the other normally open contacts of said first circuit.
4. The combination of a source of electricity and a motor in circuit therewith, said circuit including a normally open contact, a normally closed contact and a second normally closed contact; a second circuit including said source, said motor, said normally 85 open contact, a second normally open contact and a third normally open contact; a third circuit including said source, a normally open contact and a normally closed contact; a fourth circuit including said 90 source, and a normally open contact; means for closing the normally open contact of said third circuit, means adapted to be automatically operated by said motor to open the normally closed contact of said third 95 circuit after the closing of the normally open contact of said third circuit, means for closing the normally open contact of said fourth circuit, means dependent on said third circuit for closing the normally open 100 contact common to said first and second circuits, means dependent upon said fourth circuit for opening the normally closed contacts of said first circuit and for closing two of the normally open contacts of said second 105 circuit.

In testimony whereof, I hereunto affix my signature, in presence of two witnesses.

MELVIN B. BENSON.
